ATTORNEY

UNITED STATES PATENT OFFICE

LINWOOD ANDERSON PACE, OF SHREVEPORT, LOUISIANA

SCREEN

Application filed September 9, 1930. Serial No. 480,730.

This invention relates to a screen for use with the windows of automobiles and the like, the general object of the invention being to make the screen in two sections which are hingedly connected together and to provide means on the screen for engaging the grooves in the windows so that the screen can be readily placed in position and have its sections moved outwardly when the window is to be partly closed and in this position, the screen will act as a shade.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a fragmentary elevation of an automobile, showing the invention in position.

Figure 2 is a fragmentary face view of the screen, with parts in section.

Figure 3 is a vertical sectional view through Figure 1 and showing the screen in position closing a window in full lines and in partly open position in dotted lines.

Figure 4 is an enlarged detail view of a portion of the screen frame, showing how the two sections thereof are hinged together.

Figure 5 is a similar view, but taken at right-angles to Figure 4.

Figure 6 is a section on line 6—6 of Figure 1.

Figure 7 is a section on line 7—7 of Figure 2.

Figure 8 is a sectional view through the window, with the screen in raised position and acting as a shade.

Figure 9 is a section on line 9—9 of Figure 5.

Figure 10 is a detail sectional view showing the handle means of the plungers.

In these drawings, the letter A indicates the frame of the screen and B the mesh which may be formed of cloth and which has its edges connected with the cloth casing 1 which passes around the members of the frame. The end members 2 of the frame are each formed with two parts hingedly connected together, as shown at 3, and having their abutting ends beveled, as shown at 4, so that these ends limit the inward movement of the frame. The lower side member 5 of the frame is rotatably arranged in the lower ends of the end members, as shown at 6, while the top member is fastened to the upper ends of the end members or the upper sections of the end members may be formed with the top member. The members of the frame are of tubular construction as shown, and spring plungers 7 are arranged in the lower member and have rubber tips 8 on their outer ends which are adapted to engage the grooves in the window of the automobile, as shown in Figure 1. A handle piece 9 is connected to the inner end of each plunger rod and these handle pieces extend through a slot 10 formed at the center part of the lower member 5 so that by pressing the two end pieces together, the tips 8 will be drawn out of the window groove to permit the screen to be removed from the window. It will, of course, be understood that when the screen is to be placed in the window, the handle pieces are pressed together so as to contract the plungers so that the frame can be placed in the window frame and then when the handle members are released, the springs of the plungers will force the tips into the grooves. Similar tips 11 are rotatably connected with the upper portions of the side members of the frame by the screws 12 and these tips engage the groove in the window, as shown in Figures 1 and 6. By having them rotatably supported on the screen frame, the

frame can be swung upwardly and outwardly, as shown in dotted lines in Figure 3 and in full lines in Figure 8, or into a vertical position, as shown in full lines in Figure 3.

5 Substantially wedge-shaped pieces 13 of resilient material are fastened to the lower ends of the end pieces and will engage the upper edge of the sash of the window when the parts are in the position shown in Figure 8. Thus 10 these members 13 act as means for holding the screen in horizontal position, as shown in Figure 8.

From the foregoing it will be seen that when the sash is lowered and the screen placed 15 in the opening left by the sash, insects, dust, dirt and the like are prevented from entering the body of the automobile and the screen also acts as a wind break. When raised to the position shown in Figure 8, the screen 20 will act as a shade. It will be seen that by forming the screen as shown, it is not necessary to remove it from the window when the sash is to be raised, though it can be easily and quickly removed and replaced by providing the spring plungers carrying the tips 25 8 at their ends.

It will, of course, be understood that wire mesh may be used with the device as well as the cloth mesh and when the wire mesh 30 is used, the mesh will be in two sections, one section forming the upper half of the screen and the other the lower half so that when the screen is in position, the two sections will come together and form a complete screen.

35 It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:—

1. A screen for a window having grooves 45 in its sides, comprising a pair of frames, hinges connecting the frames, a wire mesh section entirely covering the pair of frames and foldable along the axis of said hinges, projections on the ends of the frame for fitting in the grooves in the window, means for moving some of the projections inwardly to disengage them from the grooves, whereby the screen section can be placed in vertical position in the window or folded on a line 50 with the hinges to have the frames moved toward each other to permit the sash to be partly closed and the screen used as an awning.

2. A screen for a window having grooves 55 in its sides, comprising a pair of frames, hinges connecting the frames, a wire mesh section entirely covering the pair of frames and foldable along the axis of said hinges, projections on the ends of the frame for fitting in the grooves in the window, means for

moving some of the projections inwardly to disengage them from the grooves, whereby the screen section can be placed in vertical position in the window or folded on a line with the hinges to have the frames moved toward each other to permit the sash to be partly closed and the screen used as a shade, a pair of plungers carrying the movable projections, and finger pieces on the plungers for manual operation thereof.

70 In testimony whereof I affix my signature.
LINWOOD A. PACE.
